UNITED STATES PATENT OFFICE.

GEORGE V. CONDON, OF BOSTON, MASSACHUSETTS, ASSIGNOR, BY MESNE ASSIGNMENTS,
TO THOMAS G. PLANT, OF BOSTON, MASSACHUSETTS.

HEEL-BAND FOR BED LASTING-MACHINES AND THE LIKE.

No. 924,967.

Specification of Letters Patent.

Patented June 15, 1909.

Application filed January 7, 1907. Serial No. 351,103.

To all whom it may concern:

Be it known that I, GEORGE V. CONDON, a subject of the King of Great Britain, residing in the city of Boston, county of Suffolk, and State of Massachusetts, have invented an Improvement in Heel-Bands for Bed Lasting-Machines and the Like, of which the following description, in connection with the accompanying drawings, is a specification, like characters on the drawings representing like parts.

This invention relates to lasting machines for boots and shoes of the type commonly known as "bed" machines or "wiper" machines.

In assembling and pulling over a boot or shoe preparatory to lasting, especially if a straight counter be used, it is customary to drive a tack through the back of the counter into the last, at a point close beside the heel seam, and at a distance of approximately one inch, more or less from the heel seat, the tack however never being completely driven in because it must subsequently be removed. The purpose of this tack is to hold the upper, counter, linings etc. in position upon the last while the shoe is being pulled over, the tack usually being permitted to remain for the purpose of holding the heel and counter of the shoe upper in position until lasted.

Lasting machines of the type referred to are usually provided with heel pads of leather or other suitable material, backed by flexible carriers or chains, which are employed to grip the shoe firmly about the heel or counter portion thereof, not only for the purpose of shaping such upper, counter etc. to the last but also to hold the last and shoe firmly during the infolding or inturning of the marginal portions thereof preparatory to tacking the latter down upon the insole. At such times it has been found that this tack, which has been driven into the back of the heel by its contact with the leather of the heel pad mutilates and destroys the latter over a considerable portion of its area because there is no uniformity in the position of the tack. After a time the heel pad becomes mutilated to such an extent that it ceases to perform its work perfectly, with a

result that renewals, with the attending expense, must frequently be made or the quality of work will fall below the required standard.

My invention aims to provide a pad which shall be free from these objections and the various features of my invention will be hereinafter disclosed in connection with a machine illustrating one embodiment thereof.

In the accompanying drawings, Figure 1 is a plan view, partially broken away, of a heel head of a typical lasting machine of the type referred to, the same being equipped with a pad illustrating one embodiment of my invention; Fig. 2 is a vertical, longitudinal section of the head shown in Fig. 1; Fig. 3, a face view of the pad shown in Fig. 1, partially spread to better show its construction; and Fig. 4 is a vertical section thereof on the dotted line 4-4, looking to the left.

Referring to the drawings, in the particular embodiment of my invention selected for illustration herein, the lasting machine, in connection with which my novel pad is employed, may be of any usual or desired type or construction. In the present instance I have shown a machine of the type illustrated in United States patent to Grandy, No. 552,834, dated January 7, 1896. The construction and operation of this machine are so well-known in the art that it is unnecessary to furnish any detailed description thereof herein. The wipers *w* operated by the handle *W*, the pad carrying chain *c*, the levers 85 upon which it is mounted, the slides 80, and the springs *s* with their associated and co-operating parts for closing and opening the pad are and may be as shown in said patent, like reference characters representing like parts in said patent, so far as said parts are therein lettered, or equivalent devices of other machines may be used if desired.

Referring to Figs. 3 and 4, the pad proper, marked 1, and composed of one or more piles of leather or other suitable material, thickened it may be at the upper edge by an inserted rand as shown, may be of any suitable or desired construction, and the material may be other than leather if desired.

Whatever the material or the construction

my invention contemplates supplying an elastic area at such point or points as the pad would otherwise be subjected to mutilation or destruction by contact therewith of 5 a tack head or other device in the process of lasting. In the present instance said pad is provided at its back portion with an opening for a rubber plug 2, shown as rectangular in shape and provided with front 10 and back flanges or lips 3-4, which retain the plug in position yet which, by reason of their shape and elasticity, permit of the insertion and removal of said plug when necessary by the compression or closing 15 together of the flanges or lips, or one of them. As shown, the front lip or flange 3 is beveled in cross section and the adjacent area of the opening therefor in the pad is correspondingly beveled or counter- 20 sunk to permit said plug to assume a normal position substantially flat or flush with the inner face of the pad. The back flange or lip 4 may be thinner, larger and more flexible since its purpose is merely to prevent 25 the plug dropping forward or from position.

When the pad is brought closely against and about the heel end of a shoe, the impressionable or rubber plug conforms to the heel end of the last with the upper thereon and to 30 any tack or other projection carried by the last or shoe; for example in Fig. 2, the tack upon meeting the surface of the rubber plug will embed itself therein, the rubber yielding readily before it without damage either to 35 the shoe, the tack or the rubber. This permits the pad proper to be closed tightly and closely about and upon the shoe, not only for proper shaping of the shoe but for sufficient and better holding thereof to permit 40 of the usual lasting by the wipers *w* at the same or at the opposite end of the last. Upon removal of the shoe, the rubber plug immediately resumes its normal position preparatory to receiving another shoe, wherein 45 the tack or device may be differently positioned from that of the preceding shoe. This rubber plug when used in connection with a tack at the back of the heel has a two-fold advantage, namely, it permits of a 50 better conformation of the pad surface to and about the heel of the shoe and it also prevents bending of the tack, with consequent mutilation of the shoe; also mutilation of the pad as the pad and shoe are 55 brought together. Another advantage of the rubber plug or its equivalent is that after the heel seat has been lasted and the operator commences to last the toe, the heel will often-times slip downward on the pad, thereby 60 throwing the shoe out of the proper angle from under the toe wipers where it was firmly set to conform to the shape of the wipers and the toe. The rubber plug holds the heel from slipping and thereby is protected 65 against this trouble. Furthermore,

when a lasting pad does not conform to the exact shape of the heel of the last, the last will hit too hard at the back of the outer curve and will not bear closely and tightly around the heel seat of the last, which is necessary to last a good heel. By inserting a section of impressionable or yielding material, for instance soft rubber, in the middle of the pad at the back, there is always sufficient resistance to press the counter against the last and yet sufficient resiliency to allow the last to sink into the pad and draw the upper edge closely around the heel seat.

My invention is not restricted to the particular embodiment thereof herein shown by way of illustration, for the same, obviously, may be variously embodied within the spirit and scope of my invention as here disclosed and claimed.

I claim—

1. A lasting machine containing in combination lasting devices and a continuous end pad with means for supporting it, said pad having an area approximately at its center more impressionable than the part of the pad surrounding the same.

2. A lasting machine containing in combination lasting devices and an end pad with means for supporting it, said pad having an area more impressionable than the body of the pad, positioned to engage the heel substantially at the median line of the counter.

3. A lasting machine containing in combination lasting devices and a continuous end pad with means for supporting it, said pad having an inserted and freely removable impressionable area substantially at its center.

4. A lasting machine containing in combination lasting devices and an end pad with means for supporting it, said pad having an impressionable and removable plug shaped to be normally retained in position.

5. A lasting machine containing in combination lasting devices and an end pad with means for supporting it, said pad having an inserted double flanged impressionable plug normally retained in position by its shape but capable of insertion and removal by change of its shape.

6. As a new article of manufacture a lasting machine pad provided with an area engaging the heel seam and its vicinity, more elastic than the main body of the pad.

7. As a new article of manufacture a lasting machine pad comprising a continuous leather pad and an inserted rubber plug at the heel thereof.

8. A lasting machine containing in combination lasting devices and an end pad having an aperture therein with means for supporting the pad, said pad having an inserted yieldable member filling the aperture.

9. In a lasting machine, the combination with lasting devices of an end pad provided with an inner surface in the vicinity of the

heel seam having greater frictional qualities than the remainder of the inner surface of the pad.

10. As an article of manufacture, a lasting pad having a continuous upper edge and provided on its inner surface with a section of material more elastic than the main body of the pad.

In testimony whereof, I have signed my name to this specification, in the presence of 10 two subscribing witnesses.

GEORGE V. CONDON.
